UNITED STATES PATENT OFFICE.

HENRY OELLRICH, OF DETROIT, MICHIGAN.

PUZZLE.

SPECIFICATION forming part of Letters Patent No. 358,620, dated March 1, 1887.

Application filed December 28, 1886. Serial No. 222,794. (No model.)

To all whom it may concern:

Be it known that I, HENRY OELLRICH, of Detroit, in the county of Wayne and State of Michigan, have invented a new and Improved 5 Puzzle, of which the following is a specification, reference being had to the annexed drawings, forming a part thereof, in which—

Figures 1 and 2 are front elevations of the puzzle, showing it in different positions; and 10 Fig. 3 is an end elevation showing the position of the parts when the puzzle is closed.

Similar letters of reference indicate corresponding parts in all the views.

My invention consists in two leaves of paste-board or analogous material connected by two pairs of straps, each pair of straps being connected with one edge of one leaf and the corresponding edge of the other leaf, so that when the leaves are opened in either direction the 20 straps act as hinges between the adjacent edges of the leaves, one pair of straps being located near opposite ends of the leaves, the other pair of straps being located near the center of the leaves and provided with two similar folding packages, one package being arranged on one side of the inner pair of straps, and the other package being arranged on the opposite side, all as hereinafter more fully described.

The leaves A B are connected together by 30 two pairs of straps, $a' a' b' b'$, the straps $a' a'$ being attached to one edge of the leaf A and to the corresponding edge of the leaf B. The straps $b' b'$ are attached to the edges of the leaves A B which are opposite those to which the straps $a' a'$ are attached.

To one side of the straps $b' b'$ is secured a sheet of paper, C, having the side flaps $c' c'$, which fold over on the central portion, D, and the end flaps $d' d'$, which also fold over on

the central portion, D. To the opposite side 40 of the straps $b' b'$ is secured a similar paper, C', provided with side flaps $c'' c''$, capable of folding over on the central portion, D', and the end flaps $d'' d''$, also capable of folding over upon the central portion. The packages 45 thus formed upon opposite sides of the straps $b' b'$ are shorter than the distance between the straps $a' a'$, so that when the packages are folded the leaves A B may be opened in either direction without the interference of the packages 50 with the straps $a' a'$.

When an object—a coin, for example—is placed in the paper C and inclosed by the flaps $c' c' d' d'$, the leaf A is closed down upon the leaf B and the leaves are turned through 55 a half-revolution in either direction, when the opening of the leaves will expose the package formed in the paper C, which will then cover the package C', inclosing the coin. The uninitiated will mistake the paper C for the paper 60 C', and will expect to find therein the coin; but upon unfolding the paper it will of course be found empty. By closing the leaves A B, reversing them, and again opening them, the paper C' will be found outermost, and upon 65 unfolding it the coin will be found inclosed therein.

Having thus fully described my invention, I claim as new and desire to secure by Letters Patent—

In a puzzle, the combination of the leaves A B, the straps $a' a' b' b'$, and the folding papers C C', attached to opposite sides of the straps $b' b'$, substantially as described.

HENRY OELLRICH.
